UNITED STATES PATENT OFFICE

JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA

WINDOW

Application filed April 10, 1928. Serial No. 268,860.

My invention relates to windows, and is more especially concerned with sliding metallic windows such as are widely used in modern fireproof buildings. Various objects and advantages of the invention are generally promoted and enhanced by sheet metal construction.

I aim to make the window proof against entrance of flame, as well as against ignition; tight against weather and draughts; and of neat and pleasing appearance, without unsightly exposure of sash cords or chains. I also aim to mount and guide the sliding sashes in a simple and convenient manner, without necessity for contact or adjustment inside the jambs. Other advantages obtainable in connection with the invention include simplicity of construction, facility in assembly and installation, and 20 relatively low cost of manufacture.

In the drawings, Fig. I is a front elevation (from outdoors) of a sheet metal window conveniently embodying my invention.

Fig. II is a view at right angles to Fig. I, 25 with various parts in vertical section as indicated by the arrows II-II in Fig. I, certain portions being broken out and omitted for the sake of showing the rest on a larger scale.

Fig. III is a horizontal section through 30 one of the jambs and the corresponding side rails of both sashes, taken as indicated by the line and arrows III-III in Fig. I, but on a larger scale.

Fig. IV is a view similar to Fig. III on a larger scale, but showing only the portion 35 of the jamb adjacent the window opening, and omitting the sash cables or chains.

Fig. V is a side view of a device for 40 attaching a sash cable to a sash.

Fig. VI is a view similar to Fig. IV illustrating a somewhat different construction.

Fig. VII is a vertical section through the meeting rails, similar to that shown in Fig. 45 II, but on a larger scale.

The window shown in the drawings comprises a frame consisting of a lintel or head 50 10, opposed jambs 11, and a sill 12, all of hollow sheet metal construction. The upper and lower vertically sliding sashes 14,

15, also of sheet metal construction, are mounted and guided in the window frame by means included in, or associated with, the exposed metal jamb facings or cheeks 16, as hereinafter described. The sash side 55 rails comprise sheet metal plates 20 extending into the corresponding jamb slots 17, 18, which are just wide enough to afford said plates some clearance or play and thus allow the sashes 14, 15 to move easily. As here 60 shown, each plate 20 is offset or joggled outward at 21 to afford space for the glass 22, and constitutes the principal structural element of the side rail. The glass 22 is held in place by a sheet metal strip 23 detachably secured to the plate 20, so as to serve as a removable glazing strip. The upper and lower rails of each sash are more or less 65 similar to the side rails in construction.

As shown in Fig. III, the sash side rail 70 plates 20 extend through the jamb cheek slots 17, 18 into the space behind the jamb cheek 16 sufficiently to afford suitable attachment for sash cables or chains 24, which extend over pulleys 25 to sash weights 26 75 in the jamb boxes. A vertical division plate 27 in each jamb box keeps the sash weights 26 from fouling one another. Edgewise movement or play of the sashes 14, 15 is prevented or limited by means outside the 80 jambs 11, co-operating with the jamb faces or cheeks 16. Preferably, the play-limiting means for both sashes 14, 15 co-operate with the jamb-cheek portion or "parting strip" 85 28 between the slots 17, 18. As shown in Fig. III, the parting strip 28 is of channel section, with its flanges 29 turned and projecting outward, away from the interior of the jamb box, and the sashes 14, 15 have correlative flange portions 30 that overlap 90 these flanges 29 so as to "weather" the sashes, besides limiting their edgewise play. As shown in Figs. III and IV, sheet metal weather strips 31 are secured against adjacent sides of the plates 20, and their margins that form the flanges 30 are offset or joggled away from the plates 20 at 32 to afford space for the parting strip flanges 29 and a slight clearance except at the edges 95 of the flanges 30, which make spring con- 100

tact with the parting strip flanges 29. The 5 edgewise play of the sashes 14, 15 is preferably limited by engagement of the free edges of the sash flanges 30 with the bottom or web of the parting strip channel 28, rather than by engagement of the outer edges of the parting strip flanges 29 against the offsets 32 in the sash weathering strips 31; accordingly, the clearance at the former 10 point is shown less than at the latter point.

The weathering strip 31 for the upper sash 14 extends between its plate 20 and the corresponding glazing strip 23, and is bent outward inside the offset 21 of said plate 15 20; while the weathering strip 31 for the lower sash 15 is at the outer side of its plate 20, and is bent out in front of the offset 21 of the latter. The conformation of the weathering strips 31 to the offsets 21 of the 20 plates 20 assures definitely correct locations of the free edges of the flanges 30. The weathering strip 31 for the upper sash 14 is also securely clamped by the glazing strip 23, and may be further positioned by engagement of the offset 32 with the edge of 25 said glazing strip.

In the present instance, the margins of the sash rail plates 20 are not exposed in the interior of the jamb box, but separately 30 housed or enclosed behind the jamb cheek or facing 16. As shown in Figs. III and IV, the enclosure is formed by a channel-like 35 depression 35 of the sheet metal forming the jamb facing 16, so as to extend around 35 behind the slots 17, 18 and the sash plate margins. This channel 35 expands inward in a dovetail cross section, and is so deep (in relation to the edge play of the sashes 14, 15 permitted by the parts 28, 30) that 40 the edges of the plates 20 can not reach its bottom. The parting strip 28 is supported from the bottom of the channel 35 by a channel-shaped member 36, and is detachably 45 secured by screws 37 taking into or through the channel bottom. To assure correct edge-wise location of the parting strip 28 and proper width of the slots 17, 18, the parting strip 28 has a central longitudinal depression 38, of width to seat accurately on the member 36, formed by embossment of the parting strip web. The sash cables 24 are 50 accommodated and housed in the jamb channel 35 behind the parting strip 28, in separate compartments or chambers 39 at either 55 side of the member 36, and are thus entirely concealed. As illustrated in Figs. III, IV and V, the sash cables (chains) 24 are attached to sheet metal straps 40, spot welded to the sash plates 20 at their lower 60 ends, and twisted and bent to throw their apertured upper ends away from said plates. The lowermost sheet metal link of each sash chain 24 has its ends separated to take the strap 40 between them, and is bolted to the 65 strap.

Owing to the enlargement of the chambers 39 to either side as compared with the widths of the slots 17, 18 and to the depth of these chambers behind the jamb cheek 16, the sash plates 20 are entirely free from contact behind the cheek 16. At one side of the cheek slots 17 or 18, each plate 20 makes a mere line contact with the bent sheet metal corner opposite the parting strip flange 29; at the other side of the groove, 75 there is only a narrow contact with the flange 29 itself.

To facilitate installation of the sashes 14, 15, a portion 44 of the jamb cheek wall at one side of the channel 35 may be made removable. As shown in Figs. III and IV, this removable portion 44 includes the inner part of the jamb cheek 16, inside the groove 18, and the corresponding side of the channel 35, as well as more than half of the 80 bottom of said channel 35. The joint 45 between the innermost edge of this removable portion 44 and the rest of the jamb box is of double hook character, formed by first bending the margin of the jamb box wall 85 outward and then retroverting it inward, and by retroverting the margin of the part 44. The margins of the removable and fixed portions of the bottom of the channel 90 95 overlap behind the member 36.

Preferably, the fixed bottom of the jamb wall channel 35 is supported at one or more points in the height of the window: as shown in Figs. III and IV, this is accomplished by a sheet metal spreader member 100 46 extending from front to rear of the jamb box against the bottom of the channel 35, and secured to the jamb box walls at either end. This member 46 may extend as a partition the whole height of the jamb, so as 105 to form a complete inner wall behind the jamb face 16. The screws 37 that secure the parting strip 28 and the member 36 take 110 into or through the overlapping halves of the channel bottom, thus clamping these parts securely together. The solid support afforded by the partition 46 makes the whole jamb cheek strong and rigid.

From the foregoing description, it will be seen that the principal wearing parts 28 and 30 on which the smooth operation and weather-tightness of the window mainly depend are relatively small and very simple, so that they can be made of superior material (such as non-corrosive bronze) and 115 workmanship without making the window excessively costly, and can easily be rolled or otherwise made true and straight. There are no contacts behind the jamb face or cheek 16 to bind, and no adjustments to get 120 out of order.

Fig. VI shows a somewhat different construction in which the sash plate flange 30* is formed by a double S-like retroversion of the weathering strip 31*, instead of by a 125 130

mere offsetting as in Fig. IV. The rear-most portion of the bottom of the jamb channel 35 has its margin retroverted and doubled flat at 45^a to give greater rigidity, and a better hold for the screw 37^a that 5 clamps the jamb wall parts together. The partition 46^a behind the channel 35 has a shallow depression 35^b that seats the retroverted margin 45^a. The partition 46^a is 10 bent toward the jamb face just in front of the channel 35, and its edge or margin is bent back in the squared bead 46^c of the jamb wall.

At the top rail of the upper sash 14 (Fig. 15 II) the plate 20^a bottoms in a groove or fold 49 of the lower sheet metal head wall 50, while the glazing strip 23^a is offset or bent laterally inward and then upward to form a channel 57 at the inner side of the plate 20^a. The weather strip 31^a is of a springy 20 bronze, and is bent back sidewise and then in the form of an inverted channel in the channel 57, with its bend upward to make contact with the shoulder formed by the 25 corner of the head groove 49. At the bottom rail of the lower sash 15, the plate 20^b is offset or joggled outward and downward, at 52, to engage the double steps 53 of the sill 12, while the glazing strip 23^b and the 30 springy weathering strip 31^b afford weathering provisions similar to those of the upper sash 14 at the head 10. The upper edge of the glazing strip 23^b is bent outward and turned downward slightly to afford 35 convenient hand-hold for raising and lowering the sash.

At the meeting rails (Figs. II and VII), the upper sash glazing strip 23^c is bent inward, downward, and upward into a 40 V-channel 55, while the lower sash glazing strip 23^d is bent outward and downward in a flange 56, corresponding in slope to the outer side of the V-channel 55. The springy weather strip 31^c of the lower sash meeting 45 rail is bent to conform to the flange 56 and its edge angled outward, but is normally more nearly vertical than the flange 56, as shown in Fig. VII, so that it shall always make spring-yielding contact with the outer 50 side of the upper meeting rail channel 55. The lower margin of the plate 20^c of the upper sash 14 is bent inward horizontally, and the upper margin of the plate 20^d of the lower sash 15 is bent outward horizontally, 55 in conformity to the corresponding portion of the glazing strip 23^d. As shown in Figs. IV and VI, the jamb face parting strip 28 may be provided with a wedge block 58 to make a tight joint with the ends of the 60 meeting rails when the sashes 14, 15 are closed.

Having thus described my invention, I claim:

1. The combination of a metal window 65 jamb cheek element embodying a longitudi-

nal channel in its face of inwardly expanding cross-section; a metal sash with a side rail plate sliding in said channel, but free from contact behind the cheek elements; a parting strip with an outwardly directed 70 weathering flange beside the channel edge; and a weathering strip on side rail plate overlapping the aforesaid weathering flange and constituting the sole means to limit edgewise play of the sash.

2. The combination of a metal window jamb cheek element formed to embody a vertical channel in its face of inwardly-expanding cross-section; a metal sash with a side rail plate sliding in said channel, but 75 free from contact behind the cheek element; an angled parting strip with an outwardly directed weathering flange mounted in the channel on the jamb cheek beside the channel edge and a weathering strip on said rail 80 plate overlapping the parting strip weathering flange and co-operating at its free edge therewith to limit edgewise play of the sash.

3. The combination of a metal window jamb cheek element formed to embody vertical channels in their opposing faces of dovetail cross-section; metal sashes with side rail plates sliding in said channels, but free from contact behind the cheek faces; and weathering means on both sashes externally 85 co-operating with opposed laterally-directed components of parting strips fitted in said channels to limit edgewise play of the sashes.

4. The combination of a metal window jamb with vertical slots in its cheek and 90 enlarged space behind the cheek, and a parting strip channel between the slots with its flanges outward; metal sashes with side-rail plates sliding in said slots, but free from contact behind the cheek plate; and weathering flanges on said plates co-operating with 95 said channel to limit the edgewise play of the sashes, and overlapping the channel flanges.

5. The combination of a metal window 100 jamb facing element embodying a vertical dovetail-section channel in its face, an outwardly directed weathering flange integral with the parting strip secured in the slot; a metal sash with a side rail plate sliding in 105 said slot, and also having a lateral glass retainer offset; and a weathering strip on said sash plate with an S-like retroversion overlapping the aforesaid flange and bent to 110 conform to the glass retainer offset portion thereof.

6. The combination of a metal window 115 frame member presenting a shoulder and a corresponding sash rail plate adapted to extend past said shoulder, with means forming a channel at one side of said plate opposite 120 said shoulder, and a weathering cushion in said channel for co-operating with said shoulder.

7. The combination with a channelled sash frame member of an oppositely arranged spring metal channel in the channel of said member for spring cushion engagement with a corresponding window frame member.
8. The combination of a sash frame member comprising juxtaposed plates with portions separated to afford a channel, and a sheet metal weather strip between said plates with its margin retroverted in said channel for spring yielding contact with a corresponding window frame member.

In testimony whereof, I have hereunto signed my name at Philadelphia, Pennsylvania, this 5 day of April, 1928.

JOAH BROGDEN.
